(57) **CLAIM**

The ornamental design for a headwear case, as shown and described.

DESCRIPTION

FIG. 1 is a front-left perspective view of a headwear case showing our new design;

FIG. 2 is a top view thereof;

FIG. 3 is a bottom view thereof;

FIG. 4 is a left view thereof;

FIG. 5 is a right view thereof;

FIG. 6 is a front view thereof;

FIG. 7 is a rear view thereof; and,

FIG. 8 is a front-left perspective view of the headwear case in an open configuration.

The portions of the headwear case shown in broken lines form no part of the claimed design.

1 Claim, 5 Drawing Sheets(56)
